UNITED STATES PATENT OFFICE.

ALBERT C. LUDLUM, OF NEW YORK, N. Y., AND ARTHUR LOWY, OF NEWARK, NEW JERSEY, ASSIGNEES TO NEW YORK ENGINEERING COMPANY, A CORPORATION OF NEW YORK.

METHOD AND APPARATUS FOR PUSHING PIPE.

Application filed June 1, 1918. Serial No. 237,715.

To all whom it may concern:

Be it known that we, ALBERT C. LUDLUM and ARTHUR LOWY, citizens of the United States, and residents of New York city, 5 in the county of New York and State of New York, and Newark, in the county of Essex and State of New Jersey, respectively, have invented certain new and useful Improvements in Methods and Apparatus for Pushing Pipe, of which the following is a specification.

This invention relates to method and apparatus for pushing pipe and has for its object to enable rods or pipes to be forced 15 through earth without the necessity of making excavations.

In carrying out the invention, we employ a method and apparatus whereby a predetermined deflection of the pipe from a 20 straight line causes an indication to be made to the operator who can then control the further movement of the pipe and cause it to resume the proper direction. Inasmuch as the character of soil varies from place 25 to place, it is desirable to provide a variable power, so that the pipe can be rapidly pushed in soft or loose earth with less power, as compared with hard or dense earth, gravel, hard pan or the like where the power 30 must be increased with diminution of the rate of movement. Between pushing strokes of the jack, the pipe is automatically gripped in order to prevent back spring and loss of available stroke caused by 35 compression of the pipe and the backing against which the pushing pressure is exerted, and to utilize the compression of the pipe to push obstructions out of the way during the selective wash boring. The machine is also 40 capable of withdrawing the pipe where desired, being so constructed that in pushing, the pipe sections are added from the rear, and in withdrawing, the pipe sections are 45 detached as withdrawn.

The apparatus consists of a reciprocating hydraulic plunger carrying jaws for gripping the pipe in pushing, together with dogs which grip the pipe and prevent back spring during the return stroke. The jack cylinder 50 is supplied by a special form of variable output pump which can be either manually or power operated. The pipe is preferably provided with internal square threads, the pipe being upset internally where threaded;

and at the forward end is provided with a 55 controlling head which carries the deflection indicating and correcting mechanism. This comprises one or more electrical contacts which remain open as long as the pipe runs true, deflection causing a contact to be 60 made and a buzzer or other signal made to the operator. The head has washing nozzles and a controlling valve having positions automatically limited by magnets in circuits with the electrical contacts. These 65 nozzles are disposed peripherally of the head and can be supplied with high pressure water from the pump in order to wash away a boulder or other obstruction, one or more of the nozzles being selectively 70 opened according to the position of the valve, the valve being actuated by the operator whenever he gets a buzzer signal indicating a deflection. Each magnet controls 75 a latch, which limits the throw of the valve, so that upon receiving the signal the operator simply has to throw the valve as far as it will go and turn on the high pressure water, in order to wash on the side where the boulder or other obstruction which has 80 deflected the pipe is located. As soon as the signal stops, the operator knows that deflection has been corrected, and can then proceed with the pushing. The operator 85 can also wash straight ahead or selectively in any lateral direction in order to facilitate the progress of the pipe. The apparatus is so constructed that, if desired, the pipe together with the controlling head can 90 be withdrawn, leaving only the extreme nozzle head in the ground.

The invention will be more fully understood in connection with the description of the accompanying drawings, wherein,

Figure 1 is a plan view of the jack, together with the backing,

Figure 2 is a side elevation,

Figure 3 is an end elevation showing the crosshead,

Figures 4 and 5, together show a longitudinal section of the forward end of the pipe, together with the washing head and the controlling head,

Figure 6 is an end elevation of Figure 4 seen from the left,

Figure 7 is a section on the line 7, 7 of Figure 4,

Figure 8 is an elevation of the pump,

Figure 9 is a section on the line 9, 9 of Figure 8.

Figure 10 is a section on the line 10, 10 of Figure 8, and

5 Figure 11 is a wiring diagram.

1 represents an annular horizontal jack cylinder, having supporting wheels 2, 2. 3 is a tank containing the pump and operated by hand lever 4. 5 is a to and from pipe 10 connected at one end to the pump discharge 6 and at the other end to the cylinder space 7 behind the annular piston 8. The annular piston 8 carries a tubular extension 9 with a pushing ring 10 which 15 abuts the rear side of the crosshead 11 sliding on guides 12. The crosshead 11 is provided with jaws 13 dove-tailed thereto on an angle as shown, the inner surfaces of the jaws being provided with forwardly 20 projecting teeth 14 which engage the pipe. For engaging the jaws with the pipe when the crosshead is to be advanced on the pushing stroke, the jaws are simultaneously engaged by a shifter ring 15 slidingly 25 mounted on the forward end of the crosshead and operated by a hand lever 16 pivoted at 17 to the lower portion of the crosshead. At the forward end of the frame, a pair of horizontally disposed dogs 18 are 30 carried by pins 19 and connected together by links 20, the dogs having teeth 21 which allow the pipe to move forward, but which dig into the pipe when it tends to spring backward. The opposite end of the cylinder 35 1 is provided with a base plate 22 which engages the backing 23. For horizontal work, a pit is ordinarily dug to receive the machine and the backing, and the pipe started horizontally at the required depth, 40 or in such other direction as is desired. The pressure is so enormous, in the case of a $3\frac{1}{2}$ inch pipe for instance running up to sixty to seventy-five tons, that a very rigid backing must be provided, and upon the 45 return stroke of the piston when the pressure has been relieved, the backing and the entire machine tend to spring forward, except as prevented by engagement of the dogs 18 with the pipe. This prevents loss of possibly 50 two inches of the effective pushing stroke which would otherwise be required to again compress the backing up to the working pressure. The maintenance of the pipe in compression by the engagement of the dogs 18 with the pipe has the further 55 effect of utilizing the enormous stresses in the pipe to push away obstructions during the selective wash boring without loss of stroke. The under sides of the guides 12 are provided with racks 25 which are engaged by pinions 26 operated by hand wheels 27 for reversing the crosshead and bringing the piston back to its initial position for another working stroke.

60 In soft homogeneous soils, or for com-

paratively short distances, where accuracy of direction is not essential, an ordinary open ended pipe can be pushed by this apparatus, as the end will only plug up with dirt for a comparatively short distance, and 70 the dirt can be washed out by water pressure when the pipe has been pushed the required distance. This method will suffice for pushing pipes from underground workings upward to the surface or horizontally 75 between different workings. Where the pipe is to be pushed a long distance under the surface with considerable accuracy, it is desirable to provide a special form of head constructed to indicate to the operator 80 at the jack when a deflection occurs, and to enable the operator to take steps to overcome the cause of the deflection. We have found that a water jet under high pressure and properly directed through the head of 85 the pipe will wash around boulders sufficiently to enable them to be pushed to one side by the pipe, or will wash through a hard strata and enable the pipe to continue its straight line of travel. Inasmuch as 90 the operator at the jack is unable to see or determine the precise character of the obstruction which deflects the pipe, means is provided whereby upon receiving an indication of deflection, as by a buzzer, the 95 operator moves the valve as far as it will go, the travel of the valve being controlled by magnets which each limit the valve to a certain open position, and each of these valve positions causing a jet of water to be 100 discharged in a different direction. The head carries a tail tube having contacts closing one or the other of these magnet circuits according to the direction of deflection, so that all that the operator has to do 105 upon getting a signal is to open the valve and turn on the water which will wash out a chamber around the obstruction until the pipe head springs back to its normal position and opens the signal circuit. The operator then proceeds with the pushing until another signal is received. Also, where it is desired to wash in front of the head to 110 reduce the power required, the operator can apply a jet for this purpose without affecting the direction.

30 is the head, which is provided with a plurality of directional nozzles, 31, 32, 33, 34, 35, 36, preferably located slightly behind the end of the head and directed diagonally forward as shown. These nozzles are connected by longitudinal passages as 37, 38 through a lining 39 to a central valve chamber 40 within the lining 39 and containing a sliding hollow valve 41 passing through a stuffing box 120 42. The valve 41 has seven positions, the first being that shown in the drawing where it is in extreme forward position, at which time the nozzles 31-36 are closed, and a valve 42 carried by the forward end of valve 125 43.

130

41 is held open by the end of the stem of valve 42 striking the central portion of the head 30. With this valve 42 open, pressure water can be supplied through valve 41, valve 5 42, to a central nozzle or nozzles 43 in the head 30, to permit washing or softening of the earth in front of the head as it is pushed. As shown, these nozzles 43 are directed radially and are shielded from the direct entrance of dirt by the short head 44. However, it has been found that nozzles cannot clog as there is always sufficient water pressure available to blow out any possible obstruction. Just in the rear of the valve 42, 10 the valve 41 is provided with a set of radial ports 45 which successively connect with the nozzles 31-36 as the valve 41 is moved rearwardly, it being seen that only one of these nozzles is open at a time. In Figure 4, the 15 successive valve positions are indicated by the dotted circles 50, 51, 52, 53, 54, 55, these circles representing the angularly located ports in the sleeve 39, but the ports 50 and 51 controlling the nozzles 32, 33 are not actually visible in the longitudinal section.

The valve 41 is actuated by means of the water supply pipe 56 which runs rearwardly through the push pipe and through the jack, and is there connected to either the jack 30 pump or to another source of supply. The valve 41 carries an external key-way 57 which engages with a key 58 carried by block 59 in the supporting tube 60. This supporting tube 60 is threaded on to the rear boss 61 35 of the head 30 by a left-hand thread 62, while the couplings of pipe 56 are with right-hand threads, thus permitting the tube 60 to be unscrewed from the head 30 by turning pipe 56 through key-way 57 and key 58 to 40 permit withdrawal of valve 41, tube 60 and all of the connected parts. The forward section 64 of the push pipe is forced on to head 30 in permanent engagement, but the remaining sections of pipe 24 are preferably 45 provided with special compression resisting square threads cut on integral upset ends of the pipe, although heavy internal couplings can be used if desired. On account of the enormous pressures to which pipes are subjected in this work, we have found that ordinary wrought iron pipe with ordinary external or internal couplings is unsuited to resist the heavy strains, whereas a special cold drawn seamless $3\frac{1}{2}$ inch pipe weighing 50 twelve to fourteen pounds per foot with integral upset ends has successfully withstood over seventy-five tons pressure.

To determine the position of the valve 41, it is provided with two lugs 66, 67, diametrically opposite to each other. For each lug 60 is provided three magnetically operated latches 68, 69, 70, 71, 72, 73, thus giving six valve positions. The latches 68-73 are normally held out of operation, but each is controlled by a corresponding magnet as 61 74, 75.

Figures 4 and 5 show the tube 60 separated from the tube 64, and carried by the rear end of tube 60 in block 59 is a tail tube 76, which extends back a sufficient distance so 70 that a slight deflection of the head 30 will throw the rear end of the tail tube 76 toward the outside pipe 24 and complete the circuit of one or the other of magnets 74, 75, etc., controlling the latches 68-73 through 75 contacts 78, 79, etc., corresponding to the several magnets. Contacts 78, 79, etc., are carried on a sleeve of insulating material carried on tube 76, each being disposed in the radial plane of the port which it controls. Each magnet is connected at one side to the valve 41 and pipe 56 and at the other side to one of the contacts 78, 79, etc., there being a contact for each magnet. When contact 78, strikes the inside of pipe 24, as will 80 happen upon sufficient deflection of the head, the corresponding magnet is energized and draws down its latch in contact with the stem of valve 41 and at the same time makes a buzzer signal at the jack. The operator 90 then pulls the pipe 56 and valve 41 rearward until the valve stops, which stopping is caused by the latch whose magnet was energized engaging one or the other of lugs 66 or 67. The operator then knows that the 95 proper side nozzle has been opened in the head on the opposite side and turns the pressure water through the pipe 56 to wash away the obstruction, which is indicated by failure of the signal caused by the tail tube resuming 100 its central position and opening the magnet circuit. The operator can then proceed with the pushing, or if he desires to wash in front of the head 30, will push the valve 41 back to its forward position to open valve 42. It 105 will be seen that as soon as the valve 41 is moved backward, the valve 42 closes so that the pressure water is all directed through the proper side nozzle. If the operator at any time desires to wash in front, he simply 110 pushes the valve 41 forward, but knows that upon again pulling the valve 41 backward it will stop when the proper side nozzle is open. When the magnet circuit is open, the springs 115 80 hold the latches all out of operation, so that the operator can at any time wash alternately both in front of and all around the head 30. The peripheral nozzles 31 to 36 around the head operate successively as valve 41 is actuated to wash all around the 120 pipe.

The form of head shown herein is of particular advantage in this kind of work as compared with a rounded or conical form of head. The latter has a camming action 125 which tends to increase the deflection of the head, especially where a hard inclined formation is encountered, while the sharp cor-

nered angular head herein shown has less tendency to deflection, and requires little or no more power. We have found that an open ended pipe works better than a rounded end pipe since the earth very quickly forms its own plug in the pipe and it thereafter acts like the blunt ended pipe.

Hydraulic power is practically the only power available for an apparatus of this character, and we have found that on account of the wide variations in the character of resistance encountered equally wide variations must be provided for at the pump. In hard ground, the pressure will run up very high but the travel will be very slow, while in soft ground the pressure need not be so high and the travel may be faster. We have devised a variable output pump which can be operated either manually or by power and providing the necessary flexibility required to secure the maximum distance in a given time.

The pump details are shown in Figures 8, 9 and 10, the pump being suitably mounted on a base and contained within the tank 3, which is filled through pipe 85, 86 being a screen. The pump consists of a casting 87 having cylinders 88, 89, 90, 91, preferably of different diameters, but having their pistons connected in pairs to crossheads 92, 93, carrying racks and engaged by a pinion 94 on rockshaft 95 and operated by the yoked hand lever 4. The suction valves 97, 98, 99, 100 are provided with elongated stems which project below the bottoms of the intake passages for each cylinder into the tank and below the water level. In order to throw any cylinder or cylinders out of operation, it is only necessary to hold its suction valve off its seat, so that while the piston goes up and down, it works idly. The suction valves are controlled by a rotary disk 103, which can move up and down on stud 104, and is connected by rods 106 to a reciprocating and rotary handle 107 carrying an arm 108 engaging with a notched segment 109 on the top of the tank. A spring 110 normally holds the handle elevated and the arm 108 in engagement with one or the other of segments 109. The disk 103 is provided with slots 111 of varying lengths, so that when the disk 103 is rotated various combinations of the four valve stems will be held effective by dropping through the slots 111 according to the angular position of the disk 103. With four cylinders of different diameters, sixteen different cylinder combinations can be obtained, varying from the maximum pump output with all inlet valves closed to the minimum pump output when all of the valves except that of the smallest cylinder 88 are held open by the solid portions of the disk 103. We have found that eight different combi-

nations furnishes sufficient flexibility for work varying from soft earth to cemented gravel, which is practically the same as soft concrete. This pump will ordinarily be operated manually, and it will be seen that when the maximum resistance is being encountered there can only be a very small volume of water pumped at each stroke. If it is desired to operate the pump by an engine, the engine is provided with a reduction gear driving a crank, and the crank is connected to a pitman 112 which is adjustably connected to the lever 4 by a clamp 113. The pump cylinders all discharge through the usual discharge valves into a common discharge 6 which is itself connected to and from pipe 5.

Figure 11 shows a form of wiring diagram, in which the pipe 56 is connected through brush 116 and wire 117 to the several magnets 74, 75, etc., these magnets being each connected to the several contacts 78, 79, etc., which complete the circuit by contacting with pipe 24 thence to battery 118, the other side of the battery being connected to a buzzer, or light 119 and thence by wire 120 to the pipe 56. The pipe 56 is ordinarily of $\frac{1}{2}$ " pipe in five foot sections, with external couplings, and wedged on each coupling, or at intermediate points, are wooden or other insulating round balls 121, which slidably support the pipe to prevent sagging and grounding of the indicating circuit through pipe 56.

When it is desired to withdraw the pipe, the machine can be turned around and operated in the same way to push the pipe in the other direction, the sections being disconnected as they come out. If desired, a double acting jack cylinder could be employed for actuating and returning the crosshead instead of the rack and pinion mechanism shown, or for pulling the pipe.

It will be understood that the method herein disclosed can be carried out with other apparatus than that herein illustrated, and also that various modifications and changes may be made in the apparatus without departing from the scope of the appended claims.

What is claimed, is:

1. In the art of driving pipe through earth in a straight line, the method which consists in effecting, by means of the deflection of the forward end of the pipe caused by an obstruction, an indication varying with the direction of deflection, and wash boring to remove said obstruction and indication.

2. The method which consists in pushing a pipe through earth, indicating deflection of the pipe, and wash boring to correct the deflection.

3. The method which consists in pushing a pipe through earth, indicating deflection of

- the pipe, and wash boring in a direction determined by the direction of deflection to correct the deflection.
4. The method of driving pipe through 5 earth, in a straight line, which consists in intermittently pushing the pipe from the rear, preventing the pipe from springing back between the strokes, and washing through the forward end of the pipe to remove deflecting obstructions.
5. In combination, a jack having means for engaging and pushing a pipe, a head carried by the forward end of the pipe having means for indicating deflection of the 15 head, and means operable through the pipe for removing the cause of deflection.
6. In combination, a jack having means for engaging and pushing a pipe, a variable output hydraulic pump for actuating the 20 jack, a head carried by the forward end of the pipe having means for indicating deflection of the head, and means operable through the pipe for removing the cause of deflection.
- 25 7. In combination, a jack having means for engaging and pushing a pipe, a head carried by the forward end of the pipe having means for indicating deflection of the head, and hydraulic means operable through 30 the pipe for removing the cause of deflection.
8. In combination, a jack having means for engaging and pushing a pipe, a head carried by the forward end of the pipe having 35 means for electrically indicating deflection of the head, and means operable through the pipe for removing the cause of deflection.
9. In combination, a jack having means 40 for engaging and pushing a pipe, a head carried by the forward end of the pipe having laterally directed nozzles, a valve within the head for selectively controlling the nozzles, and means extending through the pipe 45 for actuating the valve.
10. In combination, a jack having means for engaging and pushing a pipe, a head carried by the forward end of the pipe having laterally directed nozzles, a valve within 50 the head for selectively controlling the nozzles, and a shiftable supply pipe extending through the push pipe and connected to the valve for actuating it and supplying water to said nozzles.
- 55 11. In combination, a jack having means for engaging and pushing a pipe, a head carried by the pipe having means responsive to deflection, and means operable through the pipe for removing the cause of deflection.
- 60 12. In combination with a pipe and pushing means, a head for the forward end of the pipe having a wash boring nozzle in its end, and peripheral nozzles adjacent the 65 end.
13. In combination with a pipe and pushing means, a head for the forward end of the pipe having a wash boring nozzle therein, and a valve therefor controllable through the pipe.
14. In combination with a pipe and pushing means, a head for the forward end of the pipe having a wash boring nozzle in the end and peripheral wash boring nozzles adjacent the end, and means for separately controlling said nozzles.
15. In combination with a pipe and pushing means, a blunt ended head for the forward end of the pipe having peripheral nozzles adjacent the end, and an interior valve for selectively controlling said nozzles.
16. The combination with a push pipe, of a head having a nozzle, and a valve within the head whereby said nozzle is controlled.
17. The combination with a push pipe, of a head having a peripheral nozzle, and a valve within the head whereby said nozzle is controlled.
18. The combination with a push pipe, of a head having a plurality of peripheral nozzles, and a valve within the head selectively controlling said nozzles.
19. The combination with a push pipe, of a head having a plurality of peripheral nozzles, and a valve longitudinally movable within the head and selectively controlling said nozzles according to its position.
20. The combination with a push pipe, of a head having a plurality of peripheral nozzles, a valve movable within the head and selectively controlling said nozzles according to its position, and means for latching said valve in its open controlling positions.
21. In pipe pushing apparatus, a head having end and peripheral nozzles, a main valve movable within the head controlling said peripheral nozzles, and an auxiliary valve in said valve for opening said end nozzle when said main valve is in a certain position.
22. In pipe pushing apparatus having wash boring nozzles, a slide valve movable to selectively control said nozzles, a plurality of displaced lugs on the valve stem, and a plurality of magnetically controlled latches cooperating with said lugs.
23. In pipe pushing apparatus, a head for closing the end of the pipe, a tail tube carried thereby and extending rearwardly thereof, and deflection indicating means controlled by said tail tube.
24. In pipe pushing apparatus, a head for closing the end of the pipe, a tail tube carried thereby and extending rearwardly thereof, and deflection indicating means carried by said tail tube.
25. In pipe pushing apparatus, a head for closing the end of the pipe, a tail tube carried thereby and extending rearwardly.

- thereof, and electrical deflection indicating means controlled by said tail tube.
26. In a pipe pushing apparatus, the combination of an electric circuit, means carried by the forward end of the pipe and actuated by the flexing thereof for closing said circuit, and current actuated means for indicating such flexing.
27. In pipe pushing apparatus, a head, deflection detecting means carried thereby, and means for disconnecting said means from the head to permit withdrawal through the pipe.
28. In pipe pushing apparatus, a head, wash boring controlling means carried thereby, and means for disconnecting said means from the head whereby to permit withdrawal through the pipe.
29. In pipe pushing apparatus, a head, a wash boring controlling valve carried thereby, and means for disconnecting said valve from the head whereby to permit withdrawal through the pipe.
30. In pipe pushing apparatus, a head, deflection detecting and wash boring controlling means carried thereby, and means for disconnecting said detecting and controlling means from the head whereby to permit withdrawal through the pipe.
31. In pipe pushing apparatus having wash boring nozzles, a slide valve movable to selectively control said nozzles, a plurality of displaced lugs on the valve stem, a plurality of magnetically controlled latches cooperating with said lugs, and means responsive to deflection of the pipe for controlling one or the other of said latches according to the direction of deflection to correspondingly control the direction of wash boring.
32. In a pipe pushing apparatus, a head carrying wash boring nozzles, and a sectional pipe connected thereto and having square threaded internal joints to resist heavy compression.
33. In pipe pushing apparatus, a head having a wash boring nozzle, a pushing pipe, a water supply pipe within said pushing pipe, and spaced supports carried by said water supply pipe and bearing on said push pipe.
34. In pipe pushing apparatus, a head having a wash boring nozzle, a pushing pipe, a valve in the head controlling said nozzle, a water supply pipe within said pushing pipe and connected to actuate and supply said valve, and spaced supports carried by said water supply pipe and sliding on said push pipe.
35. In pipe pushing apparatus, a push pipe, a head having deflection operated means, means operable through the head for removing the cause of deflection, sliding means in the head for controlling said removing means, means extending through the push pipe and insulated therefrom for actuating said sliding controlling means, and a deflection indicating circuit including said push pipe, said deflection operated means, and said insulated actuating means.
36. A device for indicating the deflection of a tube, comprising an electrical circuit, a contact, an elongated support attached at one end to the tube and carrying said contact on its free end, means for completing the circuit through said contact as the tube deflects, and current actuated means for indicating such deflection.
37. A device for indicating the deflection of a tube, comprising an electrical circuit, a plurality of annularly disposed contacts, an elongated support within the tube and attached at one end thereto and carrying said contacts on its free end, said contacts normally being disposed centrally of the tube, and means for completing the circuit through one of said contacts as the latter are moved out of central position relative to the tube wall by the deflection of the tube, the particular contact in each instance being determined by the direction of the deflection, and current actuated means for indicating through which contact the circuit is completed.

Signed at New York city in the county of New York and State of New York, this 27th day of May, A. D. 1918.
